CLAIM

The ornamental design for an input device, as shown and described above.

DESCRIPTION

FIG. 1 is a view of one side of the input device, in a first position for use. The other sides of the input device look identical to the side shown in FIG. 1 when the input device is in the first position for use.

FIG. 2 is a view of the side of the input device in a second position for use in which the top has been pressed downwards. The other sides of the input device look identical to the side shown in FIG. 1 when the input device is in the second position for use.

FIG. 3 is a view of the top of the input device.

FIG. 4 is a view of the bottom of the input device; and, FIG. 5 is a perspective view of the input device in the first position for use, which shows the bottom of the input device. The broken lines in the drawings depict portions of the input device that form no part of the claim. The unshaded portions of the input device seen in-between the solid and broken lines are not claimed.

The input device is intended to be used for navigating between and within pages on a computer monitor.
